UNITED STATES PATENT OFFICE

JOHANNES GIJSBERTUS WILHELM MULDER AND EKKO OOSTERHUIS, OF EINDHOVEN, NETHERLANDS, ASSIGNORS TO N. V. PHILIPS' GLOEILAMPENFABRIEKEN, OF EINDHOVEN, NETHERLANDS, A LIMITED LIABILITY COMPANY OF THE NETHERLANDS

RECTIFYING INSTALLATION

Application filed November 18, 1927, Serial No. 234,274, and in Belgium January 29, 1927.

This invention refers to an alternating current rectifying installation adapted for full-wave rectification. According to the invention such a rectifier has in addition to 5 output terminals for full-wave supply at least one separate output terminal for half-wave supply. The output voltage in the latter case is higher than in the case of full-wave supply.

10 The rectifier of the kind referred to may comprise a supply transformer having two series connected secondary windings, the free ends of which are each connected to an anode of a rectifier. According to the invention such a rectifier may be provided by 15 at least two output terminals of the same polarity, one of said output terminals being connected to the intermediate connection of the secondary windings and the other to one 20 of the said connections leading to the anodes. In order to simplify the change of connections the said terminals of the same polarity may be connected to a common plug socket.

The invention will be more clearly understood by reference to the accompanying drawings, in which:

Fig. 1 shows, by way of example, a circuit diagram of an installation according to the invention, and

30 Fig. 2 is a plug socket which contains the two negative leads.

Referring to Fig. 1, the reference numeral 1 designates the primary of a transformer adapted to be connected to an alternating current supply. 2 and 3 are the secondary coils of the said transformer and 4 is the coil which supplies the heating current to the cathode 10 of the valve rectifier 7. The secondary coils 2 and 3 are connected to each 35 other and to a negative direct current terminal 11 across ballast resistances 5 and 6, the free ends of the said coils are connected to the anodes 8 and 9 of the rectifier, the free end of the secondary 3 also being connected to a 40 separate negative output terminal 12 whereas the middle point of the coil 4 is connected to the positive direct current terminal 13. Of course instead of the free end of the secondary coil 3 the free end of the coil 2 and 45 therewith the anode 8 might be connected

with the terminal 12. It is also possible to connect this free end with a separated terminal (not shown in the figure). The connection of the battery B with this terminal may be obtained by a switch or in another 55 manner. In Fig. 1 this connection is obtained by providing the terminals 11 and 12 with a plug socket. This plug socket is shown apart in Fig. 2. With the negative terminal of the battery is connected a plug 60 which may be put either in the plughole 14 or 15. If, in the example shown, the battery B is to be charged by the use of both half waves of the alternating current, the plug is put into the hole 14 and the current will flow 65 for alternate half waves as follows:—starting from the positive terminal 13, through the battery B to be charged, across terminal 11, through ballast resistance 5, through coil 2, to anode 8, thence to cathode 10 and finally 70 to the point of issue, i. e. the positive terminal 13. During the other half-waves the charging current flows as follows:—

Positive terminal 13, battery B, negative terminal 11, ballast resistance 6, coil 3, anode 75 9 9, cathode 10 to the positive terminal 13. If a higher charging voltage than is obtainable with full wave rectification is desired, only one half-cycle of the alternating supply current will be used and half-wave rectification will 80 be employed. For this purpose the negative pole of the battery is connected to terminal 12, the charging current flowing as follows: starting from positive terminal 13, through battery B, negative terminal 12, through coil 85 3 and variable resistances 6 and 5, through coil 2, to anode 8, cathode 10 and back to the positive terminal 13. The plug socket may be provided with signs to prevent choosing the erroneous connection for the determined 90 charge-conditions.

What we claim is:

1. An alternating current rectifying installation, adapted for full wave rectification, comprising a supply transformer having primary and secondary windings, the secondary winding being split into two sections and having an intermediate connection, a direct current load, having positive and negative terminals, a rectifier valve, having at 100

least two anodes and a cathode, each anode being connected to a separate free end of the said secondary winding, and the cathode being connected to the positive terminal for the 5 said load, the negative terminal of the said load being connected to the said intermediate connection, and a second negative terminal for the said load adapted for connection to a free end of one of the said secondary 10 transformer windings sections.

2. An alternating current rectifying installation adapted for full wave rectification, comprising a supply transformer having primary and secondary windings, the secondary winding being split into two parts and having an intermediate connection, a direct 15 current load having a positive and a negative terminal, a rectifier valve, having at least two anodes and a cathode, each anode of the said 20 rectifier being connected to a separate free end of the said secondary winding, and the cathode being connected to the positive terminal of the said load, the negative terminal of the said load being connected to the said 25 intermediate connection of the said secondary winding, a second negative terminal for the said load adapted for connection to a free end of one of the secondary transformer 30 windings and a plug socket common to the said negative terminals for connection of the direct current load to the rectifying installation.

3. An alternating current rectifying installation comprising a full-wave thermionic rectifying device, a source of alternating current supply therefor, leads extending from opposite sides of the source to the respective anodes, a connection from the cathode to the load, and means on the other side of the load 40 to selectively connect it to one point on the source for full-wave rectification and on another point for half-wave rectification at higher voltage than at full-wave rectification.

In testimony whereof we affix our signatures, at the city of Eindhoven, this 29th day 45 of October, 1927.

JOHANNES GIJSBERTUS WILHELM MULDER.
EKKO OOSTERHUIS.
